3-PYRAZOLIDONES

Charles F. H. Allen and John R. Byers, Jr., Rochester, N. Y., assignors to Eastman Kodak Company, Rochester, N. Y., a corporation of New Jersey

No Drawing. Application August 3, 1953,
Serial No. 372,148

8 Claims. (Cl. 260—310)

This invention relates to the preparation of 3-pyrazolidone compounds and particularly to the preparation of 4,4-dialkyl-3-pyrazolidones. 15

Various 3-pyrazolidones have been described in the prior art such as 1-phenyl-3-pyrazolidone and 1-phenyl-5-methyl-3-pyrazolidone having the respective structures 20

However, the 4,4-dialkyl-3-pyrazolidones have not previously been described and have unusual properties particularly as photographic developing agents. 30

The 4,4-dialkyl-3-pyrazolidones of the invention have the general formula

wherein R represents an alkyl group preferably of 1 to 4 carbon atoms such as methyl, ethyl, n-propyl, iso-butyl; or an aryl group of the benzene or naphthalene series substituted or not such as phenyl, o-tolyl, m-tolyl, p-tolyl, p-aminophenyl, o-, m-, p-methoxyphenyl, p-dialkylaminophenyl, o-nitrophenyl, o-bromophenyl, o-chlorophenyl, m-nitrophenyl, m-bromophenyl, m-chlorophenyl, p-nitrophenyl, p-benzylphenyl, p-bromophenyl, p-chlorophenyl, p-acetamidophenyl, o-, m-, p-carboxyphenyl, p-cyanophenyl, hydroxyalkylphenyl such as p-hydroxyethylphenyl, o-, m-, p-hydroxyphenyl, as well as α -naphthyl, β -naphthyl, 7-hydroxy-2-naphthyl, and other aryl groups derived from aryl hydrazines. R₁ and R₂ represent the same or different alkyl groups preferably containing from 1 to 4 carbon atoms such as those above mentioned. 45

The following are representative compounds forming a part of our invention.

1-phenyl-4,4-dimethyl-3-pyrazolidone

2

1-p-aminophenyl-4-methyl-4-propyl-3-pyrazolidone

1-p-chlorophenyl-4-methyl-4-ethyl-3-pyrazolidone

1-p-acetamidophenyl-4,4-diethyl-3-pyrazolidone

1-p-β-hydroxyethylphenyl-4,4-dimethyl-3-pyrazolidone

1-p-hydroxyphenyl-4,4-dimethyl-3-pyrazolidone

1-p-methoxyphenyl-4,4-diethyl-3-pyrazolidone

1-p-tolyl-4,4-dimethyl-3-pyrazolidone

1-(7-hydroxy-2-naphthyl)-4-methyl-4-n-propyl-3-pyrazolidone

Examples of other 3-pyrazolidones contemplated are:

- 1-p-nitrophenyl-4,4-dimethyl-3-pyrazolidone
- 1-p-cyanophenyl-4,4-dimethyl-3-pyrazolidone
- 1-p-acetylaminophenyl-4,4-dimethyl-3-pyrazolidone
- 1-p-benzylphenyl-4,4-dimethyl-3-pyrazolidone
- 1-methyl-4,4-dimethyl-3-pyrazolidone
- 1-p-carboxyphenyl-4,4-dimethyl-3-pyrazolidone
- 1-carboxymethyl-4,4-dimethyl-3-pyrazolidone
- 1-hydroxyethyl-4,4-dimethyl-3-pyrazolidone
- 1-m-aminophenyl-4,4-dimethyl-3-pyrazolidone
- 1-m-chlorophenyl-4-methyl-4-ethyl-3-pyrazolidone
- 1-m-acetamidophenyl-4,4-diethyl-3-pyrazolidene

The 4,4-dialkyl-3-pyrazolidone compounds of the invention are prepared by a novel method. A hydrazine, such as an arylhydrazine of the benzene or naphthalene series such as phenylhydrazine, is generally reacted with approximately a molecular equivalent amount of a 3-halogen-2,2-dialkyl propionyl halide such as 3-chloro-2,2-dimethylpropionyl chloride in the presence of an acid binding agent such as sodium carbonate, sodium acetate, methyl morpholine, pyridine, quinoline, isoquinoline, diarylanilines, such as diethylaniline, trialkylamines such as triethylamine and N-alkylpiperidines. In effecting the reaction it appears essential that the mentioned ingredients be combined within a rather limited range of temperature of the order of 0 to 10° C. in order to prevent side reactions such as the formation of a 5-pyrazolidone compound which materially reduces the yield of the desired product. In addition, we find that after combining the ingredients as mentioned, the yield of product is greatly increased by gradually warming up the reaction mixture as over a steam bath, and maintaining the temperature of the reaction mixture at about 100° C. until the reac-

tion is complete. For this purpose heating of the reaction mixture over a steam bath for about 1 to 10 hours produces the best yields. For example, one hour heating yields 40 percent and 4 hours' heating yields 75 percent of the theoretical amount of the 3-pyrazolidone compound. Longer heating can be expected to increase the yield somewhat and it is apparent that it is preferred that the heating be carried out for at least 4 to 5 hours or for an equivalent length of time if heating is conducted at a temperature differing appreciably from steam bath temperature.

3-halogen-2,2-dialkyl propionyl halides used in preparing the 4,4-dialkyl-3-pyrazolidones of the invention have the structure

15

20

in which X is a halogen atom and R₁ and R₂ are alkyl groups and can be prepared as described by Kharasch and Brown, J. A. C. S. 62, 925-929 (1940). 3-chloro-2,2-dimethylpropionyl chloride prepared by that process from sulfonyl chloride and trimethyl acetic acid had a boiling point of 85-86° C. at 60 mm. and the refractive index was (*n*_D²⁰ 1.4539). A satisfactory procedure is as follows:

30

3-CHLORO-2,2-DIMETHYLPROPIONYL CHLORIDE

To 156 g. (1.15 moles) of sodium hydroxypivalate in 40 a 500-ml. three-necked flask fitted with a reflux condenser and dropping funnel, 250 ml. (3.44 moles) of thionyl chloride is added slowly. The initial exothermic reaction is followed by an endothermic one. After the addition is complete, the mixture is heated on the steam cone for two hours, and occasionally shaken. The mixture is then 45 distilled at water-pump pressure. The thionyl chloride is not condensed; the chloride is collected at 97-112°/110 mm. The yield is 110-120 g. (62-68%).

3-chloro-2,2-dipropylpropionyl halide can be made in 50 a similar manner. In the case of these propionyl halides the alkyl groups in the 2-position of the propionyl halides are identical, and when these propionyl halides are reacted with the hydrazines, the resulting 3-pyrazolidone compounds contain identical alkyl groups in the 4-position (R₁ and R₂ in the above formulas).

55 The 4,4-dialkyl-3-pyrazolidones having the above formula in which R₁ and R₂ are different alkyl groups are preferably prepared by reaction of the selected arylhydrazine with propionyl halides having the above formula in which R₁ and R₂ are different alkyl groups. These 60 propionyl halides can be prepared from disubstituted acetaldehydes (R₁R₂CHCHO) such as methylpropyl acetaldehyde by reaction with formaldehyde and alkali to obtain the corresponding hydroxymethyl disubstituted acetaldehydes

65

such as hydroxymethyl-propylmethylacetaldehyde, followed by oxidation to obtain a hydroxymethyl disubstituted acetic acid, i. e.

75

such as

which is then treated with thionyl chloride to obtain the desired 2,2-dialkylsubstituted-3-chloropropionyl chloride such as 2,2-methylpropyl-3-chloropropionyl chloride which is then reacted with the selected hydrazine to obtain the corresponding 4,4-disubstituted-3-pyrazolidone.

The 1-hydroxyalkylaryl-4,4-dialkyl-3-pyrazolidone compounds having the above general formula wherein R represents a hydroxyalkylphenyl group, are prepared by the reaction of acetoxyalkylphenylhydrazines with the above described 2,2-disubstituted-3-chloropropionyl halides, followed by acidic or basic hydrolysis of the resulting 1-acetoxyalkylphenyl-4,4-dialkyl-3-pyrazolidone as described in the following examples.

1-hydroxyphenyl-4,4-dialkyl-3-pyrazolidones are prepared from acyloxyphenylhydrazines such as p-acetoxyphenylhydrazine reacted with the selected 2,2-dialkyl substituted 3-chloropropionyl chloride, such as 2,2-dimethyl-3-chloropropionyl chloride in the manner of the following examples, and subsequently hydrolyzing the resultant 1-acyloxyphenyl-4,4-dialkyl-3-pyrazolidone. The comparable 1-naphthol-4,4-dialkyl-3-pyrazolidones are prepared similarly from the acetoxyphenylhydrazines.

The 1-aminophenyl-4,4-disubstituted-3-pyrazolidones can be prepared similarly by reacting the selected acylaminophenylhydrazine such as p-acetaminophenylhydrazine with the selected 2,2-disubstituted-3-chloropropionyl chloride, e. g., 2,2-dimethyl-3-chloropropionyl chloride, followed by saponification of the resultant amide.

The 1-aminoaryl-4,4-dialkyl-3-pyrazolidone compounds can also be obtained by our process by utilizing a nitrophenyl hydrazine, such as p-nitrophenylhydrazine for reaction with the acid chloride followed by reduction of the nitro group of the resulting 1-nitroaryl-4,4-dialkyl-3-pyrazolidone.

The 1-alkyl-4,4-dialkyl-3-pyrazolidones are prepared by reaction of alkylhydrazines such as methylhydrazine or carboxymethylhydrazine, with the 3-halogen-2,2-dialkylpropionyl halides such as 3-chloro-2,2-dimethylpropionyl chloride. Thus, in this case 1-methyl-4,4-dimethyl-3-pyrazolidone is obtained from methylhydrazine.

Detailed preparation of representative compounds of our invention will now be described.

Example 1.—1-phenyl-4,4-dimethyl-3-pyrazolidone

In a 1-liter 3-necked flask equipped with a mechanical stirrer, a thermometer, and a dropping funnel are placed 240 ml. of dry pyridine and 60 ml. (66 g., 0.56 mole) of phenylhydrazine. The mixture is cooled to 5°, and the addition of 60 ml. (71 g., 0.46 mole) of 3-chloro-2,2-dimethylpropionyl chloride begun. The mixture is kept below 25° during the addition, allowed to warm to room temperature during one hour or overnight and finally refluxed for two hours.

The mixture is cooled, diluted with 300 ml. of chloroform, and extracted with several portions of 5-10% aqueous sodium hydroxide. Each extract is washed twice with a little chloroform, neutralized (to pH 6, universal indicator paper) with concentrated hydrochloric acid, cooled, and filtered. The first extracts are neutralized by the pyridine hydrochloride and yield no pyrazolidone. From later portions are obtained 64 g. (74%) of crude material. Recrystallization from aqueous methanol yields 59 g. (68%); M. P. 164-166° (uncor.). The hydrazine salts, e. g., phenylhydrazine hydrochloride can also be used in the above synthesis.

Example 2.—1-p-tolyl-4,4-dimethyl-3-pyrazolidone

2-chloro-1,1-dimethylpropionyl chloride (14 g.; 0.1 mole) is dissolved in 25 ml. of pyridine which has been cooled to 5° in an ice bath. This solution is added in four portions at 5° during 5 minutes to a slurry of 16 g. of p-tolyl-hydrazine hydrochloride in 15 ml. of pyridine. The mixture is heated on the steam bath until all has dissolved, and then heated for four more hours. Cold water (350 ml.) is stirred in during 15 minutes. The solution is scratched to start crystallization, cooled to 5°, and filtered. There is thus obtained 12.4 g. of crude 1-p-tolyl-4,4-dimethyl-3-pyrazolidone (M. P. 143-145°) which is 60% of the theoretical amount of 20.4 g.

Purification is effected by dissolving in 55 ml. of absolute alcohol and treating with Norit. The hot filtered solution is cooled to 5° and again filtered. The crystalline product is washed well with petroleum ether to remove a yellow impurity and dried. The melting range is then 148-149°.

The isomeric ortho and meta-tolyl compounds 1-*o*-tolyl-4,4-dimethyl-3-pyrazolidone M. P. 143-144° C., and 1-*m*-tolyl-4,4-dimethyl-3-pyrazolidone M. P. 105-107° C., are prepared by the above method using the corresponding ortho- and meta-tolylhydrazines or their salts.

*Example 3.—1-(*p*- β -hydroxyethylphenyl)-4,4-dimethyl-3-pyrazolidone*

$\text{p}-(\beta\text{-Acetoxyethyl})\text{phenylhydrazine hydrochloride}$ was prepared by diazotization of 33 g. of $\text{p}-(\beta\text{-acetoxyethyl})\text{aniline}$ followed by reduction of the resulting diazonium compound with 85.5 g. stannous chloride dihydrate. The diazonium compound was extracted with ether, washed with water, and dried over magnesium sulfate. The hydrazine HCl derivative was precipitated by bubbling HCl through the ether solution until no additional product separated.

The desired 3-pyrazolidone derivative was obtained by mixing an externally cooled solution of 1.6 g. of (β -acetoxyethyl) phenylhydrazine hydrochloride in 8 ml. of dry pyridine and 1.08 g. of 3-chloro-2,2-dimethylpropionyl chloride, followed by refluxing the reaction mixture for 2 hours. The resulting 1-(*p*- β -acetoxyethylphenyl)-4,4-dimethyl-3-pyrazolidone, after further extraction and recrystallization, had a melting point of 81.5-83.5° C.

A solution of 0.2 gram of 1,4-(*p*- β -acetoxyethylphenyl)-4,4'-dimethyl-3-pyrazolidone in 10 ml. of 2% hydrogen chloride-methanol was refluxed 3½ hours and evaporated to dryness under reduced pressure. The residue was taken off in 4 ml. of 5% sodium hydroxide and the small quantity of base-insoluble material was removed by an ether extraction. The basic solution was acidified to pH 6 with concentrated HCl, saturated with sodium chloride and extracted three times with ether. The ether extract was washed once with saturated brine and dried. Evaporation of the ether yielded a glossy solid which was crystallized from a mixture of ethyl acetate and ligroin, yield 0.1 gram, melting point 130-140° C. Recrystallization of this product from the same solvent pair and treatment with Norit raised the melting point to 140-143.5° C.

Representative arylhydrazines and alkylhydrazines use-

ful in preparing the compounds of the invention are, for example:

Phenylhydrazine
o-, m-, p-Tolylhydrazine
o-, m-, p-Bromophenylhydrazine
o-, m-, p-Methoxyphenylhydrazines
o-, m-, p-Nitrophenylhydrazines
o-, m-, p-Chlorophenylhydrazines
p-Cyanophenylhydrazine
o-, m-, p-Bromophenylhydrazines
p-Acetamidophenylhydrazine
p-Benzylphenylhydrazine
p-Diethylaminophenylhydrazine
Methylhydrazine
Ethylhydrazine
o-, m-, p-Carboxyphenylhydrazine
o-, m-, p-Acetoxyphenylhydrazines
p-Acetoxyethylphenylhydrazine
Carboxymethylhydrazine
Carboxyethylhydrazine
Acetoxyethylhydrazine
 α -Naphthylhydrazine
7-acetoxy-2-naphthylhydrazine

As will be apparent, representative 3-halogen-2,2-dialkylpropionyl halides which can be reacted with the above hydrazines to obtain the 4,4-dialkyl-3-pyrazolidone compounds of the invention are:

3-chloro-2,2-dimethylpropionyl chloride
3-bromo-2,2-dimethylpropionyl bromide
3-chloro-2,2-diethylpropionyl chloride
3-chloro-2,2-dipropylpropionyl chloride
3-chloro-2,2-dibutylpropionyl chloride
3-chloro-2-methyl-2-ethylpropionyl chloride
3-chloro-2-methyl-2-propylpropionyl chloride

As previously mentioned, the 4,4-dialkyl-3-pyrazolidone compounds of the invention have unique properties as photographic developing agents. It is not understood why this is true; however, it has been observed that when the compounds are used as developing agents in photographic developer compositions for the development of exposed silver halide emulsion layers, the oxidation products of the 4,4-dialkyl-3-pyrazolidone compounds obtained as a result of the development reaction are bimolecular compounds believed to have the following structure:

where the R groups in the formula are those given above. In the case of 1-phenyl-4,4-dimethyl-3-pyrazolidone, the bimolecular development product had a melting point of 181-183° C. and had the following analysis:

Calcd.: C, 70.2; H, 6.4; N, 14.9; M. wt., 376

Found: C, 70.2; H, 7.0; N, 14.8; M. wt., 366 (boiling ethyl alcohol)

The mentioned prior art compounds such as 1-phenyl-3-pyrazolidone, which contain hydrogen atoms in both the 4- and 5-positions of the pyrazolidone nucleus, are believed to form during the development of silver halide emulsions the corresponding 3-hydroxy-1-phenylpyrazole, rather than a bimolecular compound obtained from the 4,4-dialkyl-3-pyrazolidone compounds of the invention.

It is not understood what mechanism is involved which renders the 4,4-dialkyl-3-pyrazolidone compounds of the invention superior to the mentioned prior art 1-aryl-3-pyrazolidone compounds as developing agents in photography. However, the superiority of the compounds of the invention was particularly evident when they were used as auxiliary developing agents in developer compositions

having relatively low pH. For this purpose the compounds were compared in a well known developer composition compounded as follows:

		Gram per liter
5	Experimental developing agent	0.5
	Sodium sulfite	100.0
	Hydroquinone	5.0
	Borax	2.0

Three developing compositions were thus prepared, the 10 first utilizing in the developer formula above 0.5 gram of 1-phenyl-3-pyrazolidone, the second 0.5 gram of 1-phenyl-4,4-dimethyl-3-pyrazolidone, and the third 0.5 gram of 1-p-tolyl-4,4-dimethyl-3-pyrazolidone as the experimental 15 developing agents. A high-speed negative film was exposed under sensitometric conditions and samples of it developed for 3½, 5½, 8 and 11 minutes in each of the three developer compositions. The sensitometric data of these tests appear in the following table:

20	Developing Agent	Development Time (min.)	0.3 Gradient Speed	Gamma	Net Fog
25	1-Phenyl-3-pyrazolidone	3½	1,500	0.50	0.27
		5½	1,250	.69	.41
		8	900	.79	.58
		11	700	.88	.72
	1-Phenyl 4,4-dimethyl-3-pyrazolidone	3½	2,100	.40	.05
		5½	2,650	.59	.08
		8	3,100	.63	.11
		11	3,000	.74	.13
30	1-p-Tolyl-4,4-dimethyl-3-pyrazolidone	3½	3,100	.40	.06
		5½	2,900	.53	.11
		8	3,650	.67	.14
		11	4,000	.76	.19

It will be apparent from the above data that the compounds of the invention produce considerably higher speed and considerably less fog in the development of silver halide emulsions than does the 1-phenyl-3-pyrazolidone compound of the prior art. Also, it will be noted from the above data when considering the compounds of the 40 present invention per se, that the substitution of the 1-aryl nucleus of the 1-aryl-4,4-dimethyl-3-pyrazolidone compounds, as in 1-tolyl-4,4-dimethyl-3-pyrazolidone, unexplainably increases the effectiveness of the compound as an auxiliary developing agent.

The developing agents were also compared for their 45 stability in developers of relatively high pH of the order of 10. This is, developer compositions of this alkalinity are well known to undergo darkening due to aerial oxidation on standing in open vessels, which shortens their life. For this purpose, three developer compositions of pH 10, 50 each containing one of the three above developing agents in addition to hydroquinone, were aerated for 4 days in open vessels. As a result, the two developer compositions containing the developing agents of the invention darkened 55 measurably less than the developer composition containing 1-phenyl-3-pyrazolidone.

What we claim is:

1. A 3-pyrazolidone compound having the general formula

wherein R represents a member of the class consisting of 70 phenyl, tolyl, p- β -hydroxyethylphenyl, and p- β -acetoxyethylphenyl groups, and R₁ and R₂ each represent an alkyl group containing from 1 to 4 carbon atoms.

2. 1-phenyl-4,4-dimethyl-3-pyrazolidone.
3. 1-p-tolyl-4,4-dimethyl-3-pyrazolidone.
4. 1-o-tolyl-4,4-dimethyl-3-pyrazolidone.

5. 1 - m - toyl - 4,4 - dimethyl - 3 - pyrazolidone.
 6. 1 - (p - β - hydroxyethylphenyl) - 4,4 - dimethyl - 3 - pyrazolidone.

7. A process for preparing a 1-aryl-4,4-dialkyl-3-pyrazolidone which comprises reacting phenylhydrazine with a compound having the general formula

wherein R_1 and R_2 represent alkyl groups each containing from 1 to 4 carbon atoms and X represents a halogen atom, at a temperature of 0 to 10° C. in the presence of an acid binding agent, heating the reaction mixture at a temperature of about 100° C. for about 1 to 10 hours.

8. A process for preparing 1-phenyl-4,4-dimethyl-3-

10

pyrazolidone which comprises reacting phenylhydrazine with 3-chloro-2,2-dimethylpropionyl chloride at a temperature of about 0 to 10° C. in the presence of pyridine as an acid binding agent, and heating the reaction mixture at a temperature of about 100° C. for about 1 to 10 hours.
